UNITED STATES PATENT OFFICE.

ALFRED DUCASBLE, OF PARIS, FRANCE.

DESIGN FOR A TIRE.

SPECIFICATION forming part of Design No. 33,338, dated October 9, 1900.

Application filed January 15, 1900. Serial No. 1,561. Term of patent 14 years.

To all whom it may concern:

Be it known that I, ALFRED DUCASBLE, a citizen of the Republic of France, residing at Paris, France, have invented and produced 5 a new and original Design for a Tire, of which the following is a specification, reference being had to the accompanying drawings, forming part hereof, in which—

Figure 1 is a perspective view of a tire having my design. Fig. 2 is a cross-section thereof.

The leading feature of the design comprises the tire shown, which, generally speaking, may be described as having a plane tread, 15 with the edges blunt or rounded, and having sides which are curved near their bases.

In the drawings, *a* is the tread, and *b* shows

the straight sides. At the unions of the tread and sides there are curves *c*, and there are also curves *d* at the bases of the sides. 20

e shows projections or ribs extending from the sides.

Having thus described my invention, what I claim as new, and desire to secure by Letters Patent, is—

The design for a tire, substantially as shown and described.

In testimony whereof I have hereunto signed my name.

ALFRED DUCASBLE.

In presence of—

R. H. BRANDON,
J. L'HERMITE.
